US00D849718S

(12) **United States Design Patent** (10) Patent No.: **US D849,718 S**
(45) Date of Patent: ** *May 28, 2019

(54) **LOUDSPEAKER**

- (71) Applicant: **Harman International Industries, Incorporated**, Northridge, CA (US)
- (72) Inventors: **Sunghoon Park**, Shenzhen (CN); **Rafal Czaniecki**, Shenzhen (CN); **Joshua Fischer**, Shenzhen (CN)
- (73) Assignee: **Harman International Industries, Incorporated**, Northridge, CA (US)
- (*) Notice: This patent is subject to a terminal disclaimer.
- (**) Term: **15 Years**
- (21) Appl. No.: **29/613,848**
- (22) Filed: **Aug. 14, 2017**
